UNITED STATES PATENT OFFICE.

EDWARD M. COYNE, OF PITTSBURGH, PENNSYLVANIA.

SCULPTURING-MACHINE.

1,163,511.

Specification of Letters Patent.

Patented Dec. 7, 1915.

Application filed March 24, 1914. Serial No. 826,971.

To all whom it may concern:

Be it known that I, EDWARD M. COYNE, a citizen of the United States, residing at Pittsburgh, in the county of Allegheny and State of Pennsylvania, have invented new and useful Improvements in Sculpturing-Machines, of which the following is a specification.

The invention relates generally to sculpturing machines, being particularly directed to a mechanical structure through the use of which a reproduction in plastic material may be made of any subject, the construction permitting the reproduction in variously proportioned sizes with respect to the original.

The main object of the present invention is the provision of a simple type of sculpturing machine, in which the model and plastic material are mounted on synchronously operated supports with a forming tool operating on the material and controlled through the use of a guide element caused to follow the original through the use of connecting members, whereby the original is reproduced in the plastic material.

The invention in the preferred form of details will be described in the following specification, reference being had particularly to the accompanying drawings, in which:

Figure 1 is a view in elevation of the improved machine, showing the same in use. Fig. 2 is a plan of the same, partly broken away. Fig. 3 is a section on line 3—3 of Fig. 1. Fig. 4 is a section on line 4—4 of Fig. 2.

Referring particularly to the accompanying drawings, the improved machine includes a base 1 of suitable type and size, on which preferably adjacent one end, is arranged a circular wall 2, within which, secured to the base, is a pedestal 3. A stub shaft 4 is rotatably supported in the pedestal 3, being formed at the upper end with a bevel gear 5, which stub shaft through the medium of the spacing block 6 is connected by bolts 7 to a supporting platform 8. Uprights 9 are secured to the platform through the medium of brackets 10, the uprights being preferably four in number and curved throughout their lengths for the forward portion of the platform, as shown. The uprights have inwardly extending, longitudinally arranged ribs 11, which at an appropriate point are formed with shoulders 12, designed to provide supports for a seat 13.

The upper ends of the uprights support an inclosing frame made up in sections 14 and connected to the uprights by brackets 15, one 60 of the sections having hinged connection at 16 with an adjacent section to permit entrance to the interior of the frame provided by the parts described. For convenience, two of the opposed sections 14 are cut out 65 at 17 to form shoulder room in the event the original is a human being and the platform 8 is provided with a foot rest 19.

On the base 1 remote from the framework just described, is secured a pedestal 20, preferably of cruciform shape in cross section on the upper end of which are supported spaced bearing plates 21. A plate 22 is arranged between the brackets, and provided with opposing trunnions 23 to fit in bearing 70 openings 24 formed in the plates 21. A disk 25 is rotatably supported on the plate 22, a pivot 26 depending centrally from the disk and seating in an opening in the plate. The plate 22 between the trunnions is centrally depressed or offset, so that the disk 25 is in line with the trunnions, whereby the practically universal movement thus provided has its pivotal supports in the same plane.

An operating lever 27 is secured at its rear end on the disk 25 the forward end of the lever being provided with a lateral post 28, the free end of which is formed with a threaded socket 29 to removably receive 90 the guide element 30. The guide element is formed at its free end for guiding coöperation with the original to be duplicated, the removable connection of said element with the post permitting the convenient use of 95 different forms of such element. At a point mid-length the lever 27, the latter is formed with a reinforced bearing opening 31, and at a point mid-distant between said opening 31 and the universal connection previously described, said lever is formed with a similar opening 32. In other words, the openings 31 and 32 are disposed respectively at one-half and one quarter the length of the lever from its fulcrum these arrangements being merely illustrative, as it is contemplated arranging the openings at any appropriate points, in order that the reproduction or model may have a definite proportion, previously determined by the location 105 of the opening used to the original.

A cutting tool is arranged to coöperate with either of the openings 31 or 32, said tool including a bearing sleeve 33 adapted

to be rotatably mounted in the particular opening desired, in which sleeve is secured a shaft 34 projecting in parallelism to the post 28, and a cutting tool 35 projecting from the sleeve in the same direction as the post. The projection of the cutting tool beyond the sleeve is directly proportioned to the length of the guiding element as is obviously necessary, and the tool is removable secured in the sleeve to permit the use of tools of different types. A bed plate 36 is secured upon the lever 27 above its fulcrum, said bed plate supporting a motor 37 connected by a belt 38 to a belt wheel 39 secured on the free end of the shaft 34, whereby rotative movement is imparted to the cutting tool.

In direct alinement with the centers of the platform 8 and of the fulcrum of the lever 27, the base 1 is formed with bearing openings 40 and 41, shown in the present instance as located respectively at mid-length and quarter length the distance between such centers. A pedestal 42 is arranged to removably coöperate with either opening 40 or 41. A shaft 43 is rotatably mounted in the pedestal, supporting at its upper end a plate 44. The shaft 43 is provided adjacent its lower end with a bevel gear 45, and the bevel gears 5 and 45 are connected for synchronous operation by a shaft 46 supported at one end in the pedestal 3 and at the opposite end in a collar 47 secured within the pedestal 42. The shaft 46 is provided with bevel pinions 48 and 49 coöperating respectively with the bevel gears 5 and 45, so that uniform and simultaneous movement is imparted to the platform 8 and to the plate 44. That end of the shaft adjacent the terminal entering the collar 47 is squared or of angular contour as at 50, whereby to permit the application of an extension shaft 51, when the opening 41 is used to receive the pedestal 42.

The material to be formed in accordance with the original is preferably molded in a mass, as 52 about a hollow angular holding member 53 adapted to be secured to a plate 54, which is in turn removably secured to the plate 44. The holder will thus secure the mass to permit it to be operated upon, the holder being preferably of aluminum.

In use, assuming as illustrated, the use of a living original, the subject is placed within the frame upon the platform 8, and an appropriate mass of the desired material arranged upon the plate 44. In the rotation of the platform 8, which may be accomplished in any way, as by moving the same by hand as the operator may find necessary or desirable, the plate 44 is similarly rotated, so that for each corresponding portion of the original, there is at all times a

corresponding portion of the model, the similar corresponding portions maintaining the same relative positions at all times. The operator by causing the guide element to follow the outline of the original, will cause the cutting tool to follow a similar outline, and the latter by reason of its rotation will cut, chip, or otherwise form the material in exact accordance with the original.

It is therefore apparent that, through the above described construction, I have provided a simple type of machine, which will produce mechanically an exact model from an original, with the model of a predetermined proportional size with respect to the original, and that the machine is capable of utilizing any type of subject, whether animate or inanimate. The holder for the material may be of such character as to receive plastic material, or solid material, it being understood that I contemplate any desired type of holder for removable connection with the plate 44.

What is claimed is:—

1. In a sculpturing machine, a base, a platform rotatably mounted thereon, a subject receiving frame arranged upon the platform, a pedestal mounted on the base remote from the platform, a lever fulcrumed upon the pedestal, an upright to receive material to be formed, the base being formed with a plurality of openings to receive the upright, and a plurality of cutting tool bearings arranged in the lever, said bearings being disposed in direct relative proportions with respect to the length of the lever as are the upright receiving openings in the base with respect to the distance between the platform and pedestal.

2. In a sculpturing machine, a base, a platform rotatably mounted thereon, a subject receiving frame arranged upon the platform, a pedestal mounted on the base remote from the platform, a lever fulcrumed upon the pedestal, an upright to receive material to be formed, the base being formed with a plurality of openings to receive the upright, and a plurality of cutting tool bearings arranged in the lever, said bearings being disposed in direct relative proportions with respect to the length of the lever as are the upright receiving openings in the base with respect to the distance between the platform and pedestal, and means for simultaneously and similarly operating the platform and upright.

In testimony whereof I affix my signature in presence of two witnesses.

EDWARD M. COYNE.
